UNITED STATES PATENT OFFICE

HENRY T. GERDES, OF LEBANON, PENNSYLVANIA, ASSIGNOR TO HAUCK MANUFACTURING COMPANY, OF BROOKLYN, NEW YORK, A CORPORATION OF NEW YORK

DESIGN FOR A FURNACE

Application filed March 18, 1933. Serial No. 47,514. Term of patent 3½ years.

To all whom it may concern:

Be it known that I, HENRY T. GERDES, a citizen of the United States, residing in Lebanon, in the county of Lebanon and State of Pennsylvania, have invented a new, original, and ornamental Design for a Furnace, of which the following is a specification, reference being had to the accompanying drawing, forming part thereof.

Fig. 1 is a front elevation of a furnace, showing my new design.

Fig. 2 is a side view thereof.

I claim:

The ornamental design for a furnace, as shown.

HENRY T. GERDES.
